UNITED STATES PATENT OFFICE

ROBERT M. GUTHRIE, OF CHICAGO, ILLINOIS

NONSPREADING STAPLE

Application filed January 15, 1932. Serial No. 586,877.

This invention relates to a non-spreading staple, the general object of the invention being to provide a staple with a single wedge-shaped shank ending in a point and having a recess at one side thereof for receiving a wire, thus eliminating the two anchor prongs of the ordinary staple, with its liability of spreading.

Another object of the invention is to make the top part of the device adjacent the recess of hook shape, the parts so arranged that the portions under the recess will form a groove in the member through which the device is being driven, and in which the hook-shaped part enters so that there is no strain on the hook-shaped part which might be liable to bend the staple at a point where the head part joins the shank part of the recess.

A still further object of the invention is to so form the head that the blows thereon will come directly over that part of the shank between the recess and the opposite edge of the shank so that no strain will come on that part above the recess, thus reducing the chance of bending the staple when the same is being driven into a member.

This invention also consists in certain other features of construction and in the combination and arrangement of the several parts to be hereinafter fully described, illustrated in the accompanying drawing and specifically pointed out in the appended claims.

In describing the invention in detail, reference will be had to the accompanying drawing wherein like characters denote like or corresponding parts throughout the several views, and in which:—

Figure 1 is a view partly in section showing how the improved staple holds a wire to a post or other member.

Fig. 2 is a front view of Fig. 1.

Fig. 3 is a view of the improved staple.

Fig. 4 is an edge view thereof with parts in section.

In these views, the numeral 1 indicates the shank part of the staple which is of substantially wedge shape with flat sides with one edge with a less incline than the other edge and with the sides of the staple converging

to a point at the lower and smaller end of the same as shown at 2.

A substantially arcuate-shaped recess is formed in the shank adjacent the upper end thereof and opens out through sides and that edge which has the greatest inclination, but this edge from the top wall of the recess to the head 4 is perpendicular to the head and the point where the greater inclination joins the lower wall of the recess is in the same plane as this perpendicular edge as shown at 5, so that when the device is driven into a post or the like, the major portion of the shank will form a channel which is entered by the hook part 6 so that this hook part does not have to force an entrance into the wood and thus no strain comes against this part 6 as it would if the said part 6 had to force its way into the wood. This prevents any danger of the upper part of the shank bending, while the staple is being driven into the wood.

The head 4 is formed with a beveled end 7, above the recess and the line a—a drawn from the point of the staple through the central part of that portion of the shank between the recess and the opposite edge passes through the exact center of that portion of the head which comes into contact with the driving implement so that blows struck the head by a hammer or the like will be directly over this point and the strain will be taken by that part of the shank which is between the recess and the opposite edge and not by the part above the recess so that the chances of the shank bending when driven into a member are practically eliminated.

The side faces of the staple may be rough and provided with the teeth 8 to make it more difficult for the staple to be pulled from the member into which it is driven, though the head 4 facilitates the extracting of the staple by a suitable tool. This head also strengthens the hook part 6.

When building barbed wire fences it is simply necessary to drive the staple in about half way and then the wire is placed over the hook after which the staple is driven home as shown in Fig. 1, so that the wire is held in the recess as shown in Figs. 1 and 2. When building a woven wire fence, the point

of the staple is placed under the particular wire which it is desirable to fasten to the post and then the staple is driven into the post and during this operation, the edge of the staple moves the wire slightly until it passes the point 5 and then it will spring back into the recess. When fastening the bottom wires of a fence, the staples should be driven with the hooks down.

10 From the foregoing, it will be seen that I have provided a sturdy and non-spreading staple which will enable one to easily and quickly attach fence wires to posts and the like.

15 It is thought from the foregoing description that the advantages and novel features of the invention will be readily apparent.

It is to be understood that changes may be made in the construction and in the combination and arrangement of the several parts provided that such changes fall within the scope of the appended claims.

Having thus described my invention, what I claim as new is:—

20 1. A device of the class described comprising a shank of wedge shape, a head connected to the shank and an upwardly curved recess in the upper part of the shank passing through both sides and one wedge of the shank, said edge from the head to the lower wall of the recess being perpendicular to the head.

25 2. A device of the class described comprising a shank, of wedge shape, a head connected to the shank and an upwardly curved recess in the upper part of the shank passing through both sides and one edge of the shank, said edge from the head to the lower wall of the recess being perpendicular to the head, 30 one end of the head being beveled and said beveled part being located on the recess side of the shank.

35 3. A staple of the class described comprising a shank and a head on the shank, said shank having flat sides with their extremities merging to form a point and the edges of the shank converging to the point with one edge being of a greater inclination than the other, and said shank having an upwardly 40 curved recess therein adjacent the head passing through both sides and the said edge of the shank, the part of the said edge from the head to the bottom wall of the recess being perpendicular to the head and the head 45 having a beveled end located above the recess.

40 4. A staple of the class described comprising a shank and a head on the shank, said shank having flat sides with their extremities merging to form a point and the side edges 45 of the shank converging to the point with one edge being of a greater inclination than the other, and said shank having an upwardly curved recess therein adjacent the head passing through the said edge of the shank 50 and through both sides, the part of the said

edge from the head to the bottom wall of the recess being perpendicular to the head and the head having a beveled end located above the recess, and the central part of that portion of the shank between the recess and the opposite wall thereof being in vertical alignment with the point.

In testimony whereof I affix my signature.

ROBERT M. GUTHRIE.
